CLAIM

The ornamental design for a charging adaptor, as shown and described.

DESCRIPTION

FIG. 1 is a perspective view of a charging adaptor having the design of my invention;

FIG. 2 is top plan view thereof, where the top and bottom views of the design are mirror images of each other;

FIG. 3 is a front elevational view thereof;

FIG. 4 is a side view thereof, where the right and left sides of the design are mirror images of each other; and,

FIG. 5 is a rear elevational view thereof.

It being understood that the broken lines are for illustrative purposes only and form no part of the claimed design.
